UNITED STATES PATENT OFFICE.

RICHARD W. JEFFERIS, OF MERCHANTVILLE, NEW JERSEY, ASSIGNOR TO
MERRITT AND COMPANY, A CORPORATION OF PENNSYLVANIA.

METAL SHELVING.

No. 829,967.

Specification of Letters Patent.

Patented Sept. 4, 1906.

Application filed May 23, 1906. Serial No. 318,308.

To all whom it may concern:

Be it known that I, RICHARD W. JEFFERIS, of Merchantville, county of Camden, and State of New Jersey, have invented an Improvement in Metal Shelving, of which the following is a specification.

My invention relates to a combination of parts, preferably formed of metal, which may be easily assembled together to form a shelf 10 of simple and efficient construction.

It also relates to the combination of such shelves together in the formation of extended shelving, so that while each shelf or set of shelves constitutes a unit an extended system of shelving may be obtained by combining a series of such units together; and the invention relates particularly to certain features of construction whereby this combination of the units may be effected with facility.

20 In the drawings, Figure 1 is a perspective view of metal shelving embodying my improvements. Fig. 2 is a transverse section on the line A A of Fig. 1, on an enlarged scale. Fig. 3 is a plan view of a cross-bar.

25 Fig. 4 is a perspective view illustrating the preferred construction of the cross-bars and their connection with the uprights. Fig. 5 is a horizontal section through one of the uprights on the line B B of Fig. 4. Fig. 6 is a 30 perspective view of one of the supporting-posts, showing an upright fitted to it; and Fig. 7 is a perspective view of part of the shelving, showing a modification in the form of the cross-bars.

35 The shelving consists, primarily, of uprights *a*, cross-bars *b*, supported by the uprights, and shelf-pieces *c*, supported by the cross-bars. The uprights *a* are formed with longitudinal slots *d* to receive the ends of the cross-bars and consist, preferably, of longitudinally-slotted or split metal tubes. These uprights are 40 arranged in pairs with their slots facing and may be secured to the floor in any suitable manner. I prefer, however, to use the posts *e* for this purpose. These have flat bases *f*, which may be secured to the floor, and the upright portions or posts *e* correspond in shape and size with the interior of the uprights, which are fitted over them with their 45 ends resting against annular shoulders *h*. Ordinarily the posts *e* will be sufficient to hold the uprights in place without other fastenings.

The metal cross-bars are formed with slots

i in their length to receive the downturned ends of the shelf-sheets and also, when desired, to receive vertical partitions *j*. The ends of these bars are inserted in the vertical slots *d* of the uprights and are suitably secured, as by pins *k* passed through holes in the uprights and bars. The uprights may be provided with a series of holes to enable the position of the cross-bars and shelves to be adjusted.

In the construction shown in Figs. 3, 4, and 5 the slotted cross-bars are formed of two flat bars placed on edge and separated sufficiently to form the slot or space *i* between them. The pins *k* are passed through the holes in the uprights and the holes *g* in the ends of the bars. The shelves *c* preferably consist of sheet metal, having their ends flanged or bent down, as at *m*, and inserted in the slots *i*. The edges of these flanges or bends *m* may be folded or bent up on the inner side of the inner bar-pieces to secure the shelf-pieces in place. The front and back edges of the shelves may be strengthened by angle-irons *n*, over which the edges of the sheet *c* are extended with their extremities bent up under the inner faces of the vertical portions of the irons, as at *o*. These irons rest at their ends on the projecting ends of the pins *k*, which thus afford additional supports for the shelves. These irons *n* may be used at the front or back, or at both. I have shown the sheet *c* at the front, where it is bent over the iron *n*, bent out to form a curved ledge *p* for purposes of ornamental effect. The corners of the sheets *c* are suitably cut out, as at *r*, to fit the sheets about the uprights, Fig. 1. Where greater strength is required, the cross-bars may be formed of angle-irons *b' b'*, as in Fig. 7, and for long shelves or where much weight is to be carried the opposite bars may be connected by irons *s*. In Fig. 7 I have shown one of these irons connected with its bar by a plate *t*. Where partitions are required, they may be formed by sheets *j*, inserted vertically in the slots *d* of the uprights and through the slots *i* in the bars and between the downturned edges or flanges *m* and may be secured in place by bending their edges *u* over the cross-bars, Fig. 1. Where an intermediate bar is used to support the ends of two adjacent shelves, as in Fig. 1, the end flanges *m* of the successive shelves are inserted in the same slot *i*, and

where a partition also is used the slot may be made wide enough to receive it also. By making the slotted bars of two separate pieces, as shown, provision is made for adjusting the width of the slot to suit the thicknesses of metal it is to receive. Where such adjustment is not necessary, the bars may be formed of single longitudinally-slotted pieces, and at the outer ends, or where the bar is to sustain only the end of one shelf and no partition is required, single unslotted bars may be used.

What I claim as new, and desire to secure by Letters Patent, is as follows:

13. 1. Metal shelving, consisting of vertical longitudinally-slotted uprights, longitudinally-slotted cross-bars having their ends secured in the slots of pairs of opposite uprights, and shelf-pieces provided at their ends with downturned flanges inserted in the slots of said cross-bars.
25. 2. Metal shelving, consisting of upright posts adapted to be fixed to the floor, longitudinally-slotted uprights having hollow ends fitted on said upright posts, cross-bars having their ends secured in the slots of pairs of opposite uprights, and shelf-pieces carried by said cross-bars.
30. 3. In metal shelving, the combination of a pair of opposite uprights, a longitudinally-slotted cross-bar carried by said uprights, a shelf-piece having a downturned end inserted in the slot of said cross-bar, and a vertical partition also extending through said slot in the cross-bar.
40. 4. In a metal shelving, the combination of a pair of opposite longitudinally-slotted uprights, cross-bars carried by said uprights, a shelf-piece supported at the ends by said cross-bars, and a vertical partition having its edges inserted in the vertical slots of the uprights and extending adjacent to the end of the shelf-piece.
45. 5. In metal shelving, the combination of a pair of opposite longitudinally-slotted uprights, longitudinally-slotted cross-bars secured at their ends to said uprights, a partition extending through the slots of said cross-bars with its edges inserted in the vertical slots of the uprights and shelf-pieces having their ends supported by said cross-bars.
55. 6. In metal shelving, the combination of a pair of opposite longitudinally-slotted uprights, longitudinally-slotted cross-bars se-

cured at their ends to said uprights, a partition extending through the slots of said cross-bars, and shelf-pieces on each side of said partition having downturned edges inserted in the slots of the cross-bars with the 60 partition between.

7. In metal shelving, the combination of a pair of opposite longitudinally-slotted uprights, a longitudinally-slotted cross-bar for supporting shelf-pieces consisting of two 65 separate pieces having their ends inserted in the slots of the uprights and separated to form the slot between them, and means for securing said separate pieces together to the uprights.

8. In metal shelving, the combination of a pair of opposite longitudinally-slotted uprights, a longitudinally-slotted cross-bar for supporting shelf-piece consisting of two 75 separate pieces having their ends inserted in the slots of the uprights and separated to form the slot between them, and pins extending transversely through said uprights and the ends of said pieces to secure them together to the uprights.

9. In metal shelving, the combination of longitudinally-slotted uprights, cross-bars having their ends inserted in the slots of opposite pairs of uprights, pins extending transversely through said uprights and cross-bars 85 to secure said cross-bars in place with the ends of said pins projecting laterally, and shelf-pieces having their ends supported by the cross-bars and their front and back edges at the ends resting on the projecting ends of 90 said pins.

10. In a metal shelving, the combination of longitudinally-slotted uprights, cross-bars having their ends inserted in the slots of opposite pairs of uprights, pins extending transversely through said uprights and cross-bars 95 to secure said cross-bars in place with the ends of said pins projecting laterally, and shelf-pieces having their ends supported by the cross-bars, and having a longitudinal 100 edge provided with a strengthening-iron resting at its ends on the projecting ends of said pins.

In testimony of which invention I hereunto set my hand.

RICHARD W. JEFFERIS.
